UNITED STATES PATENT OFFICE.

JAMES MANDY, OF NEW YORK, N. Y., ASSIGNOR OF THIRTY-FIVE PER CENT TO LOUIS MANDY, OF NEW YORK, N. Y.

LIFE-SAVING DEVICE.

Application filed January 29, 1925. Serial No. 5,484.

This invention relates to life saving devices and apparatus, and more particularly to a novel and improved construction adapted to be attached to the body of the person whereby he may be safely lowered to the ground from a high elevation in a building.

One of the objects of my invention is to provide a novel and improved casing having a reel and brake mechanism for controlling an endless, flat band wound on said reel and adapted to be attached to a stationary object within the building so that the individual may lower himself to the ground in the same manner as if using a rope or cable.

Another object of my invention is to provide a life saving apparatus, in which the casing has attached thereto a body belt and a foot grip including a hand controlled brake mechanism, constructed and arranged on the casing so that the individual may regulate the speed of descent.

I accomplish the above objects and others which will be more fully understood and appreciated by those skilled in the art, particular reference being made to the accompanying drawings, showing an embodiment of my invention, wherein:

Figure 1 is a view showing the use of the life saving device.

Figure 2 is a front view of the apparatus showing the casing and the brake controlled mechanism.

Figure 3 is a sectional view through the casing and brake showing the body belt.

Figure 4 is an enlarged sectional view of the casing showing the flat strip or reel.

Referring now to the drawings wherein like reference characters designate corresponding parts throughout the several views, 40 5 designates the wall of a building and 6 the window frame or sash through which the individual may be lowered to the ground.

The mechanism proper consists of a casing or housing 7 preferably of metal. A 45 central shaft 8 mounted in bearings and passing through the faces 9, 10, of the casing, has connected thereto a reel formed of a flat band, preferably of metal and of a width, slightly less than the width of the casing, 50 so that when the band is unwound, it will not become tangled or prevent the person from being lowered as would be the case if a rope or cable were used. One end of the band 11 is attached to the shaft 8 and the 55 opposite end extends through an opening 12

of the casing. A hook or clip 13 is connected to the opposite end of the band so that it may be attached to a hook or permanent object in the room.

On the shaft, there is provided a brake mechanism in the form of a wheel 14, held securely by a transversely extending bar 15, said bar being attached to the casing by fastening elements 16. Between the face 10 of the casing and the wheel 14, brake bands 17 are provided which act as friction bands as the said wheel rotates and the weight of the body tends to unwind the band 11 quickly.

The friction bands 17 are intended to act 70 as a permanent brake and their pressure against the face of the casing 10 is regulated by the thumb nuts 31 and 32. When the device is tested before installing; and also at occasional inspections thereof; the said 75 screws are adjusted so that sufficient friction will be applied on revolving the wheel 14 to prevent the rapid descent of a person secured to the apparatus. This braking element acts automatically and without control 80 by the operator.

A brake band 18 is secured to the casing as shown at 19 of Figure 2, and passing around the wheel 14 is again fastened as shown at 20 to the lever 21, which is pivotally secured to the casing at 22.

Between the said brake band 18 and the wheel 14, is another band 35 which is secured as shown at 30 and 36 to the chains 28 and 29, which are joined together and 90 support a stirrup 27.

Now, referring to Figure 3 of the drawings; a strap 23 is secured to the face 9 of the casing by means of the snap hooks as shown at 24, and to this strap is secured 95 the belt 24, which is adjustable by means of buckles as shown at 25. A central supporting member 26 extends from front to rear of the said belt.

In operation; the belt 24 is secured 100 around the body of the person wishing to descend, as shown in Figure 1 of the drawings; one foot is placed in the stirrup 27, and the lever 21 is grasped in one hand. The person then eases himself over the window ledge and casts himself free. The automatic friction bands 17 will prevent any sudden momentum and the speed is controlled by applying the brake lever 21 to actuate the band 18. Now the said band 18 110

acts by applying pressure through the intervening band 35 to the wheel 14, and it may be seen that this action may be compounded by pressure on the stirrup 27 which would bring the said band 35 into direct action on the wheel 14. Thus braking power may be applied by the use of the lever 21 alone, or by the stirrup alone; or by the combined action of the two elements, which gives great range and certainty of control.

The stirrup brake would be invaluable in the case of a person secured in the apparatus and having a child in his, or her arms; as the control could then be effected by the foot 15 braking element and the hand left entirely free.

It will be seen therefore, that in my invention I have provided an apparatus having a permanent acting braking element, and other braking elements which may be used independently, or compounded at the will of the user; and all interdependent on certain elements of the said brake structure.

Having thus described my invention, what I claim as new and desire to secure by United States Letters Patent is:—

1. In an apparatus of the class described, in combination with a suitable casing and supporting elements therefor, a wheel member mounted on a central shaft, friction bands between the inner face of the said wheel, and the said casing, and means to adjust the said wheel to exert a permanent pressure on the said bands, an inwardly disposed rim on the said wheel which acts to retain the said bands in position and also serves to present a frictional bearing surface, a brake band which partially encircles same, and another brake band resting over the first mentioned brake band, and means

to apply a pressure to the said brake bands.

2. In an apparatus of the class described, the combination with a reel and casing having suitable supporting means therefor and a body belt thereon, of a triple compound braking apparatus including a recessed wheel mounted on the shaft of the said reel and having frictional members between its body portion and the said casing, a transverse bar adjustably secured to the said casing and bearing against the central portion of the said wheel, and a peripheral rim on the said wheel and a brake band resting thereon, and a stirrup suspended from the said brake band, and another band secured to the said casing and resting upon the surface of the band first mentioned, and an actuating lever secured to the said last mentioned band.

3. In an apparatus of the class described, the combination with a reel element supported within a suitable casing and having a suspension strip secured thereto, of a braking mechanism comprising a wheel mounted on the shaft of the said reel, friction rings between the said wheel and the casing of the reel element, and means to adjust the said wheel to exert a permanent pressure on the said rings, and a peripheral rim on the said wheel and a foot actuated brake band thereon, and another brake band secured to the aforesaid casing and resting upon the said foot brake band, and a lever connected to the second mentioned band, substantially as shown and described.

Signed at New York, in the county of New York and State of New York, this 14th day of January A. D. 1925.

JAMES MANDY.
